DESIGN FOR A CURTAIN FABRIC OR SIMILAR ARTICLE

Morris Poley, Larchmont, N. Y.

Application January 25, 1939, Serial No. 82,594

Term of patent 3½ years

To all whom it may concern:

Be it known that I, Morris Poley, a citizen of the United States of America, residing in Larchmont, county of Westchester, and State of New York, have invented a new, original, and ornamental design for a Curtain Fabric or Similar Article, of which the following is a specification, reference being had to the accompanying drawing, forming part thereof, wherein the figure is a plan view of a piece of curtain fabric or similar article, showing my new design.

I claim:

The ornamental design for a curtain fabric or similar article, substantially as shown.

MORRIS POLEY.
